DEFENSIVE PUBLICATION

UNITED STATES PATENT OFFICE

Published at the request of the applicant or owner in accordance with the Notice of Apr. 11, 1968, S49 O.G. 1221. Identification is by serial number of the applicant and the heading indicates the number of pages of specification, including claims, and of sheets of drawing contained in the application as originally filed. The file of this application is available to the public for inspection; reproduction may be purchased for 30 cents per sheet.

Applications published under the Defensive Publication Program have not been examined as to the merits of alleged invention. The Patent Office makes no assertion as to the novelty of the disclosed subject matter.

Class 208-10

This disclosure relates to a process for making liquid fuels from coal comprising liquefaction of ground coal in a slurry, solvent treatment of the liquefaction effluent at supercritical conditions and subsequent refining of the liquid. Optimum conditions for the unique supercritical separation step will depend upon the critical temperature of the solvent and the molecular type distribution of the feed. Temperatures may range from 220-500° F. and pressures may range from 750-5000 p.s.i.a. Suitable solvents include ethane, propane, butane, pentane, hexane, ethylene, propylene, butylene, halogenated light hydrocarbons, CO₂, ammonia, SO₂, etc. An essentially solid raffinate phase and an essentially liquid extract phase suitable for hydrocracking are recovered from the supercritical separation step.
